ALEXANDRE GUINDON, OF CLARENCE CREEK, ONTARIO, CANADA.

COMBINATION-LOCK.

1,235,463.

Specification of Letters Patent. Patented July 31, 1917.

Application filed May 5, 1916. Serial No. 95,623.

To all whom it may concern:

Be it known that I, ALEXANDRE GUINDON, a subject of the King of Great Britain, and resident of Clarence Creek, in the Province 5 of Ontario, Dominion of Canada, have invented certain new and useful Improvements in Combination-Locks, of which the following is the specification.

This invention relates to improvements in 10 combination locks and the objects of the invention are to simplify the construction of the lock and arrange the several parts so that the combination may be easily changed, and generally to adapt the several parts to 15 better perform the functions required of them.

With the above and other objects in view, the invention consists essentially of the improved construction described and set forth 20 in the following specification and accompanying drawings forming part of the same.

In the drawings,

Figure 1 is a front elevation of the improved lock.

Fig. 2 is a back elevation of the improved 25 lock.

Fig. 3 is an elevation of the lock cover showing the mechanism mounted thereon.

Fig. 4 is an elevation of the lock with the 30 cover removed to show the mechanism.

Fig. 5 is a front elevation of the catch member and latching mechanism mounted on the door.

Fig. 6 is a transverse section on the line 35 2—2 of Fig. 1.

Like characters of reference refer to like parts in the several figures.

Referring to the drawings, A represents 40 the improved combination lock operatively mounted on the door B and jamb post C and comprises the casing 10 designed to house the lock mechanism, access to the casing being obtained through the removable cover 11. Rotatably mounted on the casing 45 10 are a pair of disks 12 and 12^a provided with a plurality of reference characters around the periphery thereof designed to register with the characters engraved on the outer face of the casing, and to facilitate rotating the said disk I provide gripping members 13 mounted thereon.

The disk 12 is provided on the inner face with a stub spindle 14 carrying the pawl 15 eccentrically mounted thereon, the front of

the pawl slidably engaging the guide member 16 carried by the casing and being provided with a reduced point adapted to coact with the disk 17 secured to the inner end of the stub spindle 18 carried by the disk 12^a. 55

The disk 17 is formed with a pair of diametrically opposite recesses 19 in the periphery thereof, and located between the said recesses is a third recess 20 designed, when unlocking the lock to engage with the pawl 15. 60

If the disk 17 were only provided with the recess 20 it would be extremely easy to open the lock as it would only be necessary to hold the pawl 15 against the edge of the disk and rotate the same until the pawl 15 65 engaged the recess, but by the use of the recesses 19, this cannot be accomplished as the pawl would engage with either of the said recesses before registering with the recess 20, so that the operator must know the 70 combination before he can position the disk 17 relatively to the pawl 15, so that the point of the said pawl would engage with the recess 20. 75

The disk 17 is further provided with a 80 keyhole 21 adapted to be engaged by the inner end of a key, which is in the form of a spindle 22, slidably mounted in the casing and provided on its outer end with a gripping member 23, while intermediate of its 85 length it carries a disk 24 engaging with the outer face of the leaf spring 25 rigidly mounted on the outer face of the casing 10.

This leaf spring is inclosed in the casing 26 formed integral with the casing 10, the 90 casing 26 being provided in the outer wall with a plurality of orifices 27 designed to permit of the characters engraved on the disk 24 being readily observed by looking through the said orifice, thereby permitting 95 of the spindle 22 being rotated to a predetermined position as indicated by the said characters, so that the point of the spindle registers with the keyhole 21 in the disk 17. 100

When the inner end of the key or spindle 22 registers with the keyhole 21, the spindle 22 is then capable of being pushed inwardly into the casing, so that the point coacts with the resilient locking member 28 and displaces the same to permit of the keeper 105 member 29 being freed therefrom to release the locking member and permitting of the door being then opened.

The keeper member 29 is housed in the casing 30 mounted on the door and is provided on the inner end with a rack 31 meshing with the pinion 32 rotatably mounted 5 on the spindle 33, the opposite ends of which carry the usual door knobs 34, the pinion being prevented from lateral displacement by the plate 35 operatively mounted in the casing 30.

10 It is also desirable that the pinion 32 should be kept in intimate engagement with its coacting rack 31, and to this end the leaf spring 36 is mounted in the casing 30 and is adapted to engage at one end with the periphery of the said pinion.

The locking member 28 is also capable of being actuated from the other side of the door B by the manually operated spindle 37 slidably mounted in the casing 10 and provided intermediate of its length with a disk 38, between which and the outer face of the casing 10, the spiral spring 39 is located. The inner end of this spindle is provided with a crank arm 40, which, when the spindle has been turned to the desired position, 25 is adapted to engage with the locking member 28, and so pull the same backwardly to permit of the keeper member 29 being retracted under the manual rotation of the 30 knob 34. The disk 38 and spiral spring 39 are housed in the casing 41 formed integral with the casing 10.

The cover 11 of the casing 10 is provided on the outer face with a pair of rotatably 35 mounted disks 50 and 51, around the periphery of which numerals or like symbols are engraved, but these disks perform no functions and are only utilized as a fooling means, so that any person unacquainted with 40 the combination of the lock, would in all likelihood spend a considerable time investigating those disks without in any way solving the combination for opening the lock.

45 The assembly of the lock will be readily understood from the foregoing description.

When the lock is in use the disk 12 is rotated to withdraw the pawl 15 from engagement with the disk 17, whereupon the disk 50 12^a is rotated so that a predetermined character on its periphery will register with a predetermined character on the casing 10 and this will bring the recess 20 into alignment with the pawl 15.

55 The disk 12 is now rotated so that the predetermined character on its periphery will register with the predetermined character on the casing and during this rotation of the said disk the pawl 15 will be moved into engagement with the recess 20 so preventing any inadvertent rotation of the disk 17.

The keyhole 21 will now register with the point of the spindle 22, which, when pressed inwardly, will engage with the locking member 28 disengaging the same from the keeper

member 29, and on rotating the knob 34 the keeper member 29 will be retracted into the casing 30, so allowing the door to be opened.

If a door fitted with a lock of this description should be inadvertently closed, it 70 may be opened from the inside of the room by means of the spindle 37 which is rotated until its crank member 40 engages the locking member 28, thereby permitting of the locking member being drawn inwardly, and 75 disengaged from the keeper member 29, which may then be retracted by the rotation of the handle 34.

It will be readily appreciated that, should 80 any person unacquainted with the combination tamper with the lock, the pawl 15, would in all likelihood, be engaged with either of the recesses 19 and the disk 17 could not be rotated into the desired position, so that the keyhole 21 would not register with the point 85 of the spindle 22, and the lock would consequently remain closed.

The recesses 19 may be of any desired size 90 and duplicated, if found necessary, and are designed to form an impediment to any unauthorized person attempting to operate the lock.

It will be clear that the pawl 15 is arranged relatively to the disk 12, so that when 95 one of the characters on the said disk registers with another character on the outer face of the casing, the operator will know that the pawl is clear of the periphery of the disk 17, so that the disk 12^a may now be rotated into the desired position, whereupon 100 the disk 12 may then be rotated until the point of the pawl engages with the recess 20, this will now position the disk 17, so that the key or spindle 22 will register with the keyhole 21 and the operation above described may then be completed to effect the 105 opening or unlocking of the door.

From this description it will be seen that I have invented a lock capable of being advantageously employed on strong rooms and the like and which is of simple construction and not liable to go out of repair.

As many changes could be made in the above description and many apparently 115 widely different embodiments of my invention within the scope of the claims constructed without departing from the spirit or scope thereof, it is intended that all matter contained in the accompanying specification and drawings shall be interpreted as 120 illustrative and not in a limited sense.

What I claim as my invention is:

1. A combination lock comprising a casing, a pair of disks rotatably mounted thereon having a plurality of characters around 125 the periphery thereof designed to register with the characters on the casing, a disk operatively connected to one of the said disks provided with peripheral recesses, a spindle carrying the second disk, a pawl 130

eccentrically mounted on the spindle adapted to engage with the recesses in the recessed disk, a locking member, a keeper member coacting with the locking member and 5 silently controlled means comprising a slidably mounted spindle having a crank arm end adapted to operate the locking member.

2. A combination lock comprising a casing, a pair of disks rotatably mounted thereon having a plurality of characters around the periphery adapted to register with characters on the casing, a disk operatively connected to one of the said disks provided with peripheral recesses and having a key hole 10 therethrough, a spindle slidably mounted in the casing provided with a reduced point adapted to engage with the key hole, a disk mounted on the spindle intermediate of its ends, a leaf spring coacting with the disk, 15 a pawl eccentrically mounted on the second said disk adapted to engage with the said peripheral recesses, a locking member, a manually operated keeper member coacting with the locking member, a spindle provided with a crank arm slidably mounted 20 on the casing and adapted to engage with

the locking member, a spiral spring coacting with the last said spindle, and means for manually operating the keeper member.

3. A combination lock comprising a casing, a pair of disks rotatably mounted thereon having a plurality of characters around the periphery thereof adapted to register with the characters on the casing, a disk operatively connected to one of the said disks provided with peripheral recesses and having a key hole therethrough, a spindle having a reduced end coacting with the key hole, a pawl eccentrically mounted on the second disk adapted to coact with the said 30 recesses, a locking member, a keeper member cooperating with the locking member, a rack on the keeper member, a pinion operating with the keeper member and a manually operating spindle engaging with 35 the said pinion.

In witness whereof I have hereunto set my hand in the presence of a witness.

ALEXANDRE GUINDON.
